(57) **CLAIM**

The ornamental design for a three hole faucet and faucet handle, as shown and described.

DESCRIPTION

FIG. 1 is a front perspective view of a first embodiment of a three hole faucet and faucet handle, showing the new design; FIG. 2 is a front view of the first embodiment of the three hole faucet and faucet handle;

FIG. 3 is a rear view of the first embodiment of the three hole faucet and faucet handle;

FIG. 4 is a side view of the first embodiment of the three hole faucet and faucet handle;

FIG. 5 is another side view of the first embodiment of the three hole faucet and faucet handle;

FIG. 6 is a top view of the first embodiment of the three hole faucet and faucet handle;

FIG. 7 is a bottom view of the first embodiment of the three hole faucet and faucet handle;

FIG. 8 is a front perspective view of a second embodiment of the three hole faucet and faucet handle, showing the new design;

FIG. 9 is a front view of the second embodiment of the three hole faucet and faucet handle;

FIG. 10 is a rear view of the second embodiment of the three hole faucet and faucet handle;

FIG. 11 is a side view of the second embodiment of the three hole faucet and faucet handle;

FIG. 12 is another side view of the second embodiment of the three hole faucet and faucet handle;

FIG. 13 is a top view of the second embodiment of the three hole faucet and faucet handle; and,

FIG. 14 is a bottom view of the second embodiment of the three hole faucet and faucet handle.

The broken lines showing various elements of the three hole faucet and faucet handle are included for the purpose of illustrating non-claimed subject matter and form no part of the claimed design.
